(57) **CLAIM**

The ornamental design for an artificially intelligent early educational and language developmental companion robot, as shown and described.

DESCRIPTION

FIG. 1 is a top front perspective view of an artificially intelligent early educational and language developmental companion robot showing my new design;

FIG. 2 is a top rear perspective view thereof;

FIG. 3 is a bottom front perspective view thereof;

FIG. 4 is a front view thereof;

FIG. 5 is a rear view thereof;

FIG. 6 is a top view thereof;

FIG. 7 is a bottom view thereof;

FIG. 8 is a left view thereof; and,

FIG. 9 is a right view thereof.
